(57) **CLAIM**

We claim the ornamental design for an irregular-shaped ladder for a tree stand, as shown and described.

DESCRIPTION

FIG. 1 is a left side isometric view of the ladder;
FIG. 2 is a right side isometric view of the ladder;
FIG. 3 is a top view of the ladder;
FIG. 4 is a left side view of the ladder;
FIG. 5 is a front view of the ladder;
FIG. 6 is a right side view of the ladder;
FIG. 7 is a back view of the ladder; and,
FIG. 8 is a bottom view of the ladder.
The broken lines are for illustrative purposes only and form no part of the claimed design.
